Primary Examiner — Jonathan J Han*Assistant Examiner* — Adrienne Corna(74) *Attorney, Agent, or Firm* — Greer, Burns & Crain, Ltd.(57) **CLAIM**

The ornamental design for a footwear midsole, as shown and described.

DESCRIPTION

FIG. 1 is a front perspective view of a footwear midsole showing my new design;

FIG. 2 is a rear perspective view thereof;

FIG. 3 is a side elevational view thereof; and,

FIG. 4 is a bottom view thereof.

The broken lines in FIGS. 1-4 represent portions of the footwear that form no part of the claimed design. The broken line which defines the bounds of the claimed design forms no part thereof.

1 Claim, 4 Drawing Sheets(56)
